Primary Examiner — Angela J Lee

(57) **CLAIM**

The ornamental design for a stand and keyboard for tablet computer, as shown and described.

DESCRIPTION

FIG. 1 is a first perspective view of a stand and keyboard for tablet computer in an assembled status showing my new design;

FIG. 2 is a second perspective view thereof;

FIG. 3 is a third perspective view thereof;

FIG. 4 is a fourth perspective view thereof;

FIG. 5 is a fifth perspective view of the stand and keyboard for tablet computer in a disassembled status;

FIG. 6 is a sixth perspective view of the stand and keyboard for tablet computer in a disassembled status;

FIG. 7 is a seventh perspective view of the stand and keyboard for tablet computer in a disassembled status; and,

FIG. 8 is an eighth perspective view of the stand and keyboard for tablet computer in a disassembled status.
